UNITED STATES PATENT OFFICE.

AXEL G. BERGMAN, OF NEW YORK, N. Y., ASSIGNOR TO ORDNANCE ENGINEERING CORPORATION, OF NEW YORK, N. Y., A CORPORATION OF NEW JERSEY.

HAND-GRENADE.

1,330,425.

Specification of Letters Patent. Patented Feb. 10, 1920.

Application filed November 13, 1916. Serial No. 130,949.

To all whom it may concern:

Be it known that I, AXEL G. BERGMAN, a subject of the King of Sweden, residing in the borough of Manhattan, city, county and State of New York, have invented certain new and useful Improvements in Hand-Grenades; of which the following is a specification.

This invention relates to hand grenades or similar devices, and aims to provide certain improvements therein.

The invention is particularly directed to that type of grenade which is intended to explode on impact with the ground or other object at which it may be directed. In this type of grenade it has been heretofore proposed to provide a firing pin which is held back by a pivoted member the lower end of which engages a pin, and the upper end of which is provided with a weight, so that when the impact occurs the weight will move by inertia to tilt the member and thereby disengage its lower end from the firing pin. In the use of such devices, however, accidental dropping of the grenade results in a premature explosion which, in many instances, has proved fatal to those immediately surrounding the grenade. It has frequently happened that during the act of throwing the thrower has been shot down, or that the grenade has accidentally struck a part of the trench, or in some other manner has received sufficient shock to explode it.

According to the present invention I provide a construction in which all danger of accidental explosion is practically eliminated. To this end I provide a safety device which can only operate in the flight of the grenade. If the grenade is not in flight it is practically impossible for it to explode unless it is deliberately and intentionally exploded by the operator.

According to the preferred form of the invention I provide a member which is preferably housed in the grenade and which is ejected therefrom during the act of throwing, such member being adapted to act by atmospheric pressure to release the detent, which permits the firing mechanism to act upon impact. Such a device, which I have denominated a "parachute", is preferably made in conventional parachute form and best comprises a square or octagon of cloth attached to the detent by cords or other

flexible members permitting the cloth to become extended or distended by atmospheric action.

In the drawings, wherein I have shown one form of the invention,—

Figure 1 is an exterior view of a grenade containing the invention:

Fig. 2 is a longitudinal axial section thereof.

Referring to the drawings let A indicate the grenade as a whole which, in the instance shown, comprises a bomb portion B and handle portion C. These may conveniently consist of two tubular casings connected together by screwthreads or in any suitable way. The casing B has a chamber D within it which contains the explosive charge, and depending within this casing is a cylinder E containing at its bottom a firing charge F with an appropriate firing cap. A firing pin G is usually provided, which is urged downwardly by a spring H. The firing pin extends through the casing B into the casing C and is there provided with an arm I which engages with a similar arm J fixed to a weight K which is pivoted to rock universally on the cross piece L which is formed with a socket-receiving point M of the weight. The broader features of this construction have been heretofore proposed. It will be observed that the spring H places a tension on the firing pin which is fixed to the weight at a point so near its pivot that it requires a considerable jar or impact to disturb the connection. When the grenade strikes the ground or other object so that it is forcibly arrested in its flight, the inertia of the weight causes it to tilt, thus disengaging the arms I and J and permitting the firing pin to explode the cap and ignite the charge.

In this type of grenade there has been danger of a premature explosion due to the possibility that the grenade in the act of throwing will hit some hard object as the side of the trench or that the soldier will be shot during the act of throwing, thus causing him to drop the grenade, and I have heretofore proposed some types of safety device to prevent this action.

According to the present invention I provide a construction which practically eliminates all danger of premature explosion by introducing a means to prevent the firing

except after the grenade is in actual flight. This means acts preferably by atmospheric pressure and best comprises a parachute which is released when the grenade is thrown, and being retarded by the pressure of air, acts to remove a detent which unlocks the firing mechanism permitting it thereafter to explode on impact.

In the construction shown as an illustration the detent is in the form of a split pin N which enters a recess in the top of the weight K and preferably has a frictional engagement therewith. This detent is shown as carried on a disk O fitting fairly snugly into the cylinder C and resting on top of the weight. So long as the parts are in this position the weight cannot tilt. Attached to the plate O is a parachute P, the attachment preferably being by a flexible member such as the cord Q. Assuming that the parachute is out of the grenade, atmospheric pressure will cause it to inflate so that it is retarded whereupon the plate O and pin N will be drawn from the grenade.

It is desirable if not necessary that an ejecting means be provided for throwing the parachute from the grenade, and in the construction shown this is simply attained by the provision of a spring R resting against the plate O and preferably having arranged above it a celluloid or other light disk S, the function of which is to prevent the material of the parachute and the connecting cords from becoming entangled with the spring. I have found in practice that a parachute of approximately ten inches in diameter constructed of light silk is admirable in its operation and occupies such a small compass that it can be easily stored in the top of a grenade which is as small as that indicated in the drawing.

The casing B is provided at its top with a closure such as T which is shown as fitting loosely to the casing, and to maintain the cover in place against the ejective action of the spring R a catch U is provided which has an upper portion U' fitted over the top of the cover, and a depending portion U² which is apertured to fit loosely over a pin U³. About midway of the length of the catch the latter is perforated to fit over a pin U⁴ and again to fit over a pin U⁵ near the bottom of the catch. The catch is normally retained in place by a collar V which surrounds the lower part of the casing C and which carries a thumb piece W engaging the lower end of the catch. When this thumb piece is in place the catch is prevented from movement. When the thumb piece is actuated to the right or left the catch is released and it is permitted to spring off the grenade through its own action or through the assistance of the spring R. Usually the collar V is drilled at one side to receive a cotter pin X which passes

into the metal of the grenade and normally prevents the accidental movement of the sleeve and hence the thumb piece W.

When the grenade is assembled and loaded in the factory the pin X is inserted and remains in position until the grenades are delivered at the trench, when the pins may be removed. In this condition the grenade is still safe against accidental discharge. If in handling the grenades prior to flight the sleeve V should be accidentally rotated to cause the thumb piece to release the catch U, the latter would be thrown off, thus releasing the cover T and permitting an ejection of the parachute. But even in these circumstances the grenade still has an almost perfect factor of safety since the mere ejection of the parachute is not sufficient to remove the pin N. It requires a deliberate and intentional pull on the connecting cord or else the pressure of atmosphere in flight to remove this pin. However, the mere removal of the pin is not sufficient to cause an explosion since after the removal an impact or shock is necessary to release the firing pin.

It will thus be seen that I have secured an almost perfect factor of safety in devices of this type.

In operation the user grasps the handle portion of the grenade and either before or during the throw disengages the thumb piece. As the grenade leaves the hand the catch flies off together with the cover and the parachute is ejected. Within a short distance from the operator sufficient atmospheric pressure is developed to withdraw the firing pin, whereupon the grenade is in condition to explode upon reaching its mark.

A noticeable feature of the invention is that the parachute device apparently does not disturb the aim nor decrease the throw of the grenade. If any action of this kind takes place it is so slight as not to be observable in actual practice.

While I have shown and described one form of the invention it will be understood that I do not wish to be limited thereto since various changes may be made therein without departing from the spirit of the invention.

What I claim is:—

1. In a grenade or the like, a firing mechanism, means for actuating said firing mechanism on impact or shock, a weight operated detent for said means, an atmospherically operable device for releasing said detent, and means for controlling the operation of said device.

2. In a grenade or the like the combination of a firing mechanism, a weight operated detent for locking said firing mechanism, a parachute device connected with said detent, a spring beneath said parachute device adapted to eject the latter, a retaining

means for the parachute, and hand-controlled means for releasing said retaining means when the grenade is thrown.

3. In a grenade or the like, the combination of firing mechanism, a weight for operating it on shock or impact, a disk above said weight engaging the latter and preventing its effective movement, a parachute above said disk and connected with the 10 latter by a flexible member, and means for retaining said parachute in inoperative condition until the grenade is thrown.

4. In a grenade or the like the combination of a firing mechanism, a weight adapted 15 to operate said mechanism upon impact, a disk above said weight engaging the latter and preventing its effective movements, a spring above said disk, a parachute above said spring, and means for retaining said 20 parachute in inoperative condition until the grenade is thrown.

5. In a grenade or the like the combination with a firing mechanism, of a detent for locking said firing mechanism, a lock 25 coöperating with said detent and normally preventing movement thereof, and an atmospherically operable device connected to the

last mentioned lock and acting to move the latter when the grenade is thrown to permit operation of the detent upon impact.

30

6. In a grenade or the like the combination with a firing mechanism, of a weight operated detent for locking the firing mechanism, a second lock which normally coöperates with the detent to prevent movement 35 thereof, and an atmospherically operable device connected with the last mentioned lock and acting to release the latter when the grenade is thrown, to permit movement of the detent upon impact.

40

7. In a grenade or the like, the combination with a casing and a firing mechanism, of a lock which in normal position prevents operation of the firing mechanism, and is movable out of the casing to permit operation of the firing mechanism upon impact, and a device which is discharged from the casing by atmospheric action and is directly connected to said lock and acting to carry the latter with it out of the casing when the 45 50 grenade is thrown and before impact.

In witness whereof, I have hereunto signed my name.

AXEL G. BERGMAN.
